UNITED STATES PATENT OFFICE.

DAVID HENRY ELKINS, OF AMESBURY, MASSACHUSETTS, ASSIGNEE TO GRAY & DAVIS, INC., OF BOSTON, MASSACHUSETTS, A CORPORATION OF MASSACHUSETTS.

LAMP.

1,170,519.

Specification of Letters Patent.

Patented Feb. 8, 1916.

Application filed May 25, 1915. Serial No. 30,303.

To all whom it may concern:

Be it known that I, DAVID H. ELKINS, a citizen of the United States, residing at Amesbury, in the county of Essex and State 5 of Massachusetts, have invented certain new and useful Improvements in Lamps, of which the following is a specification.

The object of the invention is the production of a lamp especially adapted for use on 10 automobiles which, first, shall be provided with a door or cover detachably secured to the body by means easily and quickly manipulated and which will maintain a tight joint between the door and body; and, secondly, which shall have the reflector yieldingly or spring supported between the door and body whereby excessive vibrations and clattering will be prevented.

The invention consists in certain novelties 20 of construction and combinations of parts as herein set forth and specified in the claims.

The accompanying drawing illustrates an example of the embodiment of the invention, 25 the parts being constructed and combined according to the best mode of procedure I have so far devised for the purpose.

Figure 1 is a vertical section in elevation taken on the line $y-y$ of Fig. 2. Fig. 2 is 30 a half front elevation view and a half sectional view, the section being taken in front of the reflector. Figs. 3, 4 and 5 are detail views illustrating the means for detachably locking the door to the body. Fig. 6 is a 35 detail view partly in section showing the means for holding the glass or lens in position. Fig. 7 is a detail of the door or cover illustrating the lug which fastens the door to the top of the body. Fig. 8 illustrates in 40 perspective one of the three sets of the yielding or spring lugs and spring rim for supporting the reflector.

Referring to the several figures, 1 designates the body or shell of the lamp of a general concavo-convex shape, and having a 45 cylindrical rim 2 at its front. To the inner surface of this rim are secured by solder at three places, each at equal distances from the others, three inwardly projecting yielding metallic or spring lugs a , a and b , the lug b being bent outwardly, as shown in Fig. 8, and each lug a having a bearing c

against which the outer peripheral edge of the reflector frictionally bears when in place. The reflector 3 is fashioned to have a circular recess 4 within which is located so as to project therefrom a cord 5 of yielding textile material. The metal of the reflector is spun or bent back some distance from the recess 4 for the cord and then turned to form 60 a disk flange 6, the same being of less diameter than the diameter of the body rim 2 so the flange may bear against the yielding lugs a and beneath the lugs b . The flange 6 has three notches 7 which allow the flange 65 to pass the lugs b when the notches register with the lugs and by rotating the reflector upon its axis the reflector flange will become frictionally locked between the lugs a and the lugs b . When the reflector is in its 70 normal position the outer surface of the flange 6 is substantially in the same plane as the outer edge of the rim 2 of the body, as indicated by the dotted line x , top of Fig. 1. 75

The door or cover for the lamp comprises an exterior ornamental molding or ring 8 of a general concavo-convex shape in cross section having an inner edge 9 and an exterior edge 10; an integral interior ring or 80 molding 11 having an exterior cylindrical flange 12 and an interior flange 13 united by a rectangular body portion comprising the vertical part 14 and the horizontal part 15, the flange 13 bearing against the edge 9 of 85 the molding 8 and the flange 12 being soldered to the edge 10 of said molding; and a lens or glass 16 bearing against the inner edge 9 of the molding 8 and held in place by a plurality of spring lugs 17 struck up 90 around the part 15 of the interior molding 11, as shown by Fig. 6.

It will be observed that when the door or cover is in place the glass bears against the cord 5 which serves as a cushion for the 95 same, that the exterior edge 10 of the molding 8 and flange 12 fit over the rim 2 of the body, and that the vertical part 14 of the ring 11 frictionally engages the disk flange 6 of the reflector when the glass has engaged and compressed the cord 5. The glass and the reflector are thus both held in their normal positions under cushioning and spring or yielding tension so they cannot 100

clatter and so dust cannot pass the glass to the interior of the reflector.

The door or cover is removably held in position by novel fastening means. The 5 rim 2 has a slot 18 and the door or cover a lug 19 removably seated within the slot, see top of Fig. 1 and Fig. 7. The lower interior of the door or cover has a slot 20 which registers with a slot 21 in the rim 2, see in 10 particular Fig. 5, and through these slots the end 22 of a pivoted lever 23 may be caused to pass and the lever be locked in position. The lever 23 is located inside the body and pivoted by a pin 24 and perforated lugs 25 to perforated lugs 26 on a plate 27 secured by solder to the inner surface of the body. A spring 28 may be used to withdraw the end 22 from the slots when the lever is unlocked. The pivoted lever is 15 operated in one direction and locked by an operating or locking lever 29 having a short arm 30 and a long curved arm 31, the arm 31 being narrower than the arm 30 and passed through a slot 32 in the body, the 20 metal adjacent serving as a fulcrum. The short arm 30 being too wide to pass through the slot, the metal at each edge bears against the metal bounding the slot. In Fig. 5 and bottom of Fig. 1 the pivoted lever is shown 25 locked by the short arm 30 turned to engage the power arm of the pivoted lever so it cannot turn, and in Fig. 4 the parts are shown in unlocked position. Turn the handle 31 of the locking lever backwardly 30 in Fig. 1 and the end of the pivoted lever is withdrawn from the slot, and the lower edge of the door or cover may then be pulled 35 out and the lug at the top of the door or cover be lifted out of the slot in the rim, as 40 is obvious.

In replacing the door or cover the lug 19 is inserted in the slot 18 and the lower edge of the cover gently moved into position, the glass first pressing against the cord 5 and 45 the flange 6 pressing against the yielding lug α within the edge of the rim and when the cover is locked the reflector is securely held so it cannot move and clatter, and the rim 2 of the body is also held in frictional 50 contact with the door or cover.

The several parts are easily fashioned, the locking means easily manipulated, and when assembled for use there is no loose element or elements which can move relative to another or one another and clatter or occasion abrasion or frictional wear on the parts.

What I claim is:

1. The combination in a lamp, of a body or shell having a cylindrical rim with a plurality of sets of yielding lugs disposed about the inner surface of said rim the lugs of each set being located in substantially parallel planes; a reflector having a flange with notches whereby the said flange can be 60 placed between the lugs lying in different

parallel planes and rotated about its axis to a locked position, a packing or cord of yielding material being located in a plane parallel with the flange and in front of the same; a removable door or cover provided 70 with an inner edge, a glass or lens in frictional contact with said edge, and an outer edge lapping over the cylindrical rim of the body; and means for detachably locking the door or cover to the rim of the body; the 75 said glass or lens engaging the packing or cord and pressing the flange of the reflector against the lugs at the inner surface of the rim of the body, whereby the glass is cushioned and the reflector held against clattering vibration.

2. The combination in a lamp, of a body or shell having a cylindrical rim with a plurality of sets of yielding lugs disposed about the inner surface of said rim, the lugs of 80 each set being located in two substantially parallel planes; a reflector having a flange with notches whereby the said flange can be placed between the lugs lying in parallel planes and rotated about its axis to a locked 85 position, a packing or cord of yielding material being located in a plane parallel with the flange and in front of the same; a removable door or cover comprising a molding 90 substantially concavo-convex in cross section having an inner edge with a glass or lens in contact therewith and a ring of angular shape in cross section secured to the rear surface of said molding and provided with a part, as 14, with a surface adapted 95 to frictionally engage the disk flange of the reflector when the cord has been compressed by the glass, the outer flange of the molding overlapping the rim of the body; and means for detachably locking the door or cover to 100 the rim of the body.

3. The combination in a lamp, of a body having a rim, a reflector having a flange, means for supporting the flange of the reflector upon the rim of the body, a packing 110 located upon the reflector and in front of the flange, a door or cover having a glass which engages the said packing and an edge which overlaps the rim of the body, and means for detachably securing the door or 115 cover to the body consisting of a lug upon one of said members seated within a slot in the other member, and a pivoted lever located upon and secured to the interior surface of the body at the opposite side of the 120 body and cover and having an end seated within registering slots in the rim of the body and the cover, means being provided for locking and unlocking said lever.

4. The combination with a lamp body, of 125 a detachable door or cover and means for securing the door or cover to the body consisting of a lug on one of the members seated within a slot in the other member, a pivoted lever at the opposite edge of the body and 130

cover, said lever secured to the inner surface of the body and the end thereof seated within a slot in the door or cover, and a locking lever pivoted within a slot in the body, 5 one arm being adapted to engage the pivoted lever and hold it from turning upon its pivot when in one position and releasing the lever when in another position, the other

end of the locking lever being located outside the body and serving as a handle. 10

In testimony whereof I affix my signature in presence of two witnesses.

DAVID HENRY ELKINS.
